United States Patent Office.

HENRY ROTHFELDER, OF NEW YORK, N. Y.

Letters Patent No. 67,138, dated July 23, 1867

IMPROVEMENT IN WINDING AND SETTING WATCHES.

The Schedule referred to in these Letters Patent and making part of the same.

TO ALL WHOM IT MAY CONCERN:

Be it known that I, HENRY ROTHFELDER, of No. 189 Broadway, of New York, in the county and State of New York, have invented a new and useful Improvement in Winding and Setting Watches; and I do hereby declare that the following is a full, clear, and exact description thereof, which will enable those skilled in the art to make and use the same, reference being had to the accompanying drawing, forming part of this specification, in which drawing—

Figure 1 represents a front view of my invention, when the same is adjusted for winding the watch.

Figure 2 is a similar view, when the same is adjusted for setting the watch.

Figure 3 is a transverse section of the ring and handle of the watch-case, the line $z z$, fig. 1, indicating the plane of section.

Similar letters of reference indicate corresponding parts.

This invention relates to an improvement on that class of watches which are wound and set by turning a button extending down through the handle of the watch-case.

My invention consists in the arrangement of a lever which carries two wheels, and which is adjustable by means of a spring and lever-catch, in combination with the wheel secured to the arbor or barrel of the spring, and with a pinion mounted on the central arbor, which carries the hands, in such a manner that, by releasing the lever-catch, the gear adjusts itself for setting the watch, and the operation of setting can be accomplished without requiring any exertion in keeping the wheels in gear, and by pressing back the lever-catch, the gear is adjusted for winding; and when the lever-catch occupies this position, it does not project beyond the periphery of the case, and consequently is not liable to catch in any portion of the pocket or wearing apparel of the person using the watch. The button, which serves to operate the winding and setting gear, is secured to the barrel of a watch-key, which is held in position by a pin secured to the ring. This ring is provided with a cam-shaped shoulder, so that by turning said ring down the pin releases the barrel, and the key can be used as an ordinary watch-key.

A represents a watch-case, which encloses the watch-movement. Under the dial, which is removed in the drawing, is situated the gear for winding and setting the watch. This gear is composed of a wheel, *a*, which is mounted on a stud, *b*, and gears in a pinion, *c*, and in two wheels *d e*. The pinion *c* is mounted on a spindle, *f*, the outer end of which is square to fit the barrel *g* that extends through the handle of the case, and is provided with a button, *h*, so that by turning said button the spindle *f* and the wheel *a* are revolved. The barrel *g* is retained in the handle of the watch-case by a pin, *i*, which is secured in one end of the ring *j*; and which catches into an annular groove in the barrel, provided the ring is in an upright position, as shown in fig. 1. But if the ring is turned down to the position shown in fig. 3, the cam-shaped shoulder *k* on said ring bears against the surface of the handle, and the pin *i* is withdrawn from the annular groove in the barrel *g*, so that the same can be withdrawn and used as an ordinary watch-key. The wheels *d* and *e* are attached to a lever, *B*, which has its fulcrum on a pivot, *l*, and which is subjected to the action of a spring, *m*, which has a tendency to press the same out in the direction of the arrow marked thereon in fig. 1, and the loose end of said lever is prevented from rising up or getting out of position by a plate, *n*, secured to the top plate of the watch-movement. When the lever *B* is allowed to follow the action of the spring *m*, it assumes the position shown in fig. 2, and in this case the wheel *e* is thrown in gear with the pinion *o* mounted on the central arbor *p* of the watch-movement, which also carries the hands. At the same time the wheel *d* is brought in such a position that it clears the wheel *q*, which connects with the main-spring in such a manner that by turning it in the proper direction said spring is wound up. But when the lever is pressed back to the position which it occupies in fig. 1, the wheel *d* is thrown in gear with the spring-wheel *q*, and the wheel *e* is thrown out of gear with the pinion *o* on the central arbor. In order to retain the lever *B* in this latter position, a lever-catch, *r*, is applied, which, when pressed back, drops over the stud *s*, and when the said lever-catch occupies this position, (as shown in fig. 1,) its outer end is situated within the circumference of the watch-case, so that it is not liable to catch in the pocket or other parts of the wearing apparel of the person wearing the watch, and at the same time it retains the lever *B* and the winding-gear in such a position that the watch can be wound up simply by turning the button *h*. It

will be noticed that when the lever B occupies this position, the wheel e is not in gear with the hand arbor, and consequently the watch can be wound without disturbing the hands.

If it is desired to set the watch, the lever-catch is forced back so that it releases the stud s, and the lever B is permitted to follow the action of the spring m, and to assume the position shown in fig. 2. In this position the wheel d is thrown out of gear with the main-spring wheel g, and by turning the button h the watch can be set. It will thus be seen that by the combined action of the lever-catch and the spring, the gear is always held in the required position either for winding or setting the watch, and either of these operations can be performed without the necessity of keeping the wheels in gear by a continuous pressure with the fingers.

What I claim as new, and desire to secure by Letters Patent, is—

1. The lever B, lever-catch r, stud s, and spring m, in combination with the wheels d, e, a, and g, and with the button h, all constructed and operating substantially as and for the purpose set forth.
2. The cam-shaped shoulder k on the ring j, in combination with the pin i and barrel g, constructed and operating substantially as and for the purpose described.

HENRY ROTHFELDER.
